STORAGE RACK UNIT ACCESSORY

Donald S. Burns, Corona Del Mar., and John L. Williams, Anaheim, Calif., assignors, by mesne assignments, to Ekco Products Company, Chicago, Ill., a corporation of Delaware

Filed Apr. 25, 1958, Ser. No. 730,975

4 Claims. (Cl. 211—71)

The present invention relates to racks and similar equipment for handling and storing articles in organized spaced apart relation and more particularly a rack unit accessory for joining a pair of self supporting mobile type rack units in fixed spaced apart relation to provide an additional rack means between said pair of mobile units.

It is an object of the present invention to provide a rack unit accessory of the character indicated which is separable to facilitate transportation and storage thereof when not in actual use, and which is easily assembled and demountably secured on the rack units to be joined thereby.

It is also an object of this invention to provide a rack unit accessory combining the advantages of strength and simplicity of construction, relatively inexpensive manufacturing cost, as well as sanitary and attractive design.

These, together with other objects and advantages which will become apparent, reside in the details of construction and assembly as more fully hereinafter described and claimed, reference being had to the accompanying drawings forming a part hereof, in which:

Fig. 1 is an expanded top perspective view, with parts broken away, showing a rack installation embodying the use of a rack unit accessory in accordance with the present invention.

Fig. 2 is an enlarged end elevation disclosing details of assembly between a self supporting rack unit and a rack unit accessory as contemplated by this invention.

Fig. 3 is an enlarged fragmentary sectional view taken along line 3—3 of Fig. 2.

Fig. 4 is an enlarged sectional view taken along line 4—4 of Fig. 2.

Fig. 5 is an enlarged fragmentary section taken along line 5—5 of Fig. 2.

A pair of mobile self supporting storage racks of identical design and construction are illustrated in the drawings in conjunction with a rack accessory unit for the purpose of presenting a specific embodiment of the present invention as applied to such pair of racks. As shown, each of said pair of racks includes a first inverted U-shaped tubular frame having legs 10 and 11 joined in spaced parallel relation by an upper bridge section 12 and a second similar frame having legs 13 and 14 joined in spaced parallel relation by an upper bridge section 15. These frames are rigidly joined in spaced parallel relation at a uniform distance apart by an upper bracing member 16 having opposed parallel arms 17, a lower bracing member 18 having opposed parallel arms 19, and an intermediate bracing member 20 having opposed parallel arms 21. Thus the arms 17, 19 and 21 at one side of the members 16, 18 and 20 provide rigid horizontal supports joining the legs 10 and 13 while the arms 17, 19 and 21 at the opposite side of members 16, 18 and 20 provide similar supports joining the legs 11 and 14 of each of the pair of rack frames. Each of the legs 10, 11, 13 and 14 may be provided with adjustable feet so that the racks may be levelled despite irregularities in the floor. In

2

other instances, the legs may be fitted with caster wheels 22 for convenience in moving the racks from place to place. Horizontally extending shelf or pan supporting runners 23 bridging the area between the legs 10 and 13 at selected vertically spaced apart positions are provided by means of a runner section 24 secured to and connecting the legs 10 and 13 of each rack unit frame and similar runners 23 extending between the legs 11 and 14 in horizontal alignment with the runners 23 extending between legs 10 and 13 are provided by means of a similar runner section 24 secured to and connecting the legs 11 and 14. The runners 23 and 24 thus provide supporting means with which pans, shelves or the like have downward engagement and on which such pans, etc. may slide while moved into and out of a supported position on the racks.

While accordingly functioning as storage racks, and with the aid of an accessory rack unit as contemplated by the present invention, said racks are adapted to be joined in fixed spaced relation at a selected distance apart and the area therebetween made available for similar storage of additional pans, shelves, etc. Such an accessory unit, as shown in Fig. 2, includes a series of bridging members 25, 26 and 27 of uniform size and dimension and each provided at opposite endwise portions thereof with a pair of downwardly bent hook portions 28 joined by an integral connecting member 28a. As shown in the drawings, the hooks 28 of bridging member 25 have engagement with the arm 17 of upper bracing member 16 at one side of one of the racks and with the arm 17 of the upper bracing member 16 of other rack. Hooks 28 of bridging members 26 and 27 have similar engagement with the arms 17 of the intermediate and lower bracing members 20 and 18 respectively. While thus supported in operative position between the racks to maintain said racks in fixed spaced apart relation, the bridging members 25, 26 and 27 provide horizontally extending load supporting shelves across the space between the racks. As shown in Fig. 5, the connecting member 28a is offset in the direction of the area within the hook portions 28 joined thereby. Thus stress is applied by the connecting member 28a against the surface of the arm of the bracing member opposite thereto to yieldably resist accidental unfastening of the hook portions 28 from a position of operative engagement with said arm of the bracing member. An accessory unit forming the subject of this invention also provides means for utilizing the area between the bridging members 25, 26 and 27 for the storage of pans, shelves, etc. in the same manner that such pans, shelves, etc. are accommodated by the supporting runners 23 of the rack units. Accordingly, the accessory unit includes a pair of end members, each consisting of a pair of legs 29 and 30 connected in spaced parallel relation by supporting runners 31 arranged in parallel spaced apart relation along said legs 29 and 30. The legs 29 and 30 are provided at their upper ends with a hook portion 32 for detachable engagement with the arms 17 of the racks on which the upper bridging member 25 is supported. The legs 29 and 30 are thus suspended from the arms 17 of the racks to position the runners 31 of each end member in horizontally paired alignment so that said runners 31 function in the same manner as the runners 23 of the rack unit. Each of the legs 29 is made up of an upper section and a lower section joined by a plate 33 to which said sections are welded. The legs 30 likewise comprise upper and lower sections joined by a similar plate 34. Similar plates 35 and 36 are secured to the lower ends of the lower section of the legs 29 and 30 respectively. When the legs 29 and 30 are in supported position on the arms 17 of the racks, the plates 33 and 34 are positioned opposite the arm 21 of the middle bracing member 20 and the plates 35 and 36 are situated opposite the arm 19 of the lower

bracing member 18. Each of the plates 33 and 34 are joined by a bolt 38 to clamping members 37 engaging the arm 21 to establish an interlocked connection between the legs 29 and 30 and the rack on which said legs 29 and 30 are supported. The plates 35 and 36 are likewise joined by a bolt 38 to clamping member 37 engaging the arm 19 of the lower bracing member 18.

As thus assembled and operatively connected to the racks, the accessory unit forming the subject of this invention affords strong, rigid, low cost storage facilities utilizing as its end supports the sides of self supporting storage racks to which said accessory unit is connected.

The ease with which the accessory unit of this invention can be applied to and removed from a state of operative assembly is highly advantageous in that it renders assembling and re-arranging of the storage facilities to suit a wide range of requirements a very simple and easy matter.

Obviously the invention is not limited to the details of the illustrated accessory unit or to the details of the rack units to which it is applied since these details may be variously modified. Moreover, it is not indispensable that all the features of the invention be used conjointly since various features may be used to advantage in different combinations and sub-combinations.

What is claimed is:

1. A rack installation comprising a pair of rack units, each being supportable in self standing relation to the other unit and provided with caster-mounted wheels, and means for detachably joining said units in fixed spaced apart relation for collective movement as a single unit, said means including bridging members detachably connected to said rack units, said bridging members each providing horizontally disposed load supporting surface across the space between said rack units when the latter are so joined, and each of said rack units provided with a detachable frame member supported in upright relation along the side of the rack unit facing the space between said rack units, and each of said frame members having runners, with the runners of each frame in horizontal alignment with the runners of the other frame, said runners extending inwardly of the space between said rack units to provide surfaces with which separate load supporting members disposed between said frame members have supporting engagement.

2. A rack installation according to claim 1, wherein each frame member has detachable connection to its supporting rack unit via means including a hook provided at the upper end of each frame engageable with cooperating means on the rack unit.

3. A rack installation according to claim 1, wherein each frame member has detachable connection to its supporting rack unit via means including a series of clamping members on each rack unit to which the associated frame member is joined by a bolt.

4. A rack installation comprising a pair of rack units, each being supportable in self standing relation to the other unit, means for detachably joining said units in fixed spaced apart relation, said means including bridging members detachably connected to said rack units, each said bridging member providing a horizontally disposed load supporting surface disposed across the space between said rack units when the latter are so joined, and each of said rack units provided with a detachable frame member supported in upright relation along the side of the rack unit facing the space between said rack units, and each of said frame members having runners, with the runners of each frame in horizontal alignment with the runners of the other frame, said runners extending inwardly of the space between said rack units to provide surfaces with which separate load supporting members disposed between said frame members have supporting engagement.
